United States Patent Office.

WILLIAM OLLER, OF SCENERY HILL, PENNSYLVANIA, ASSIGNOR TO HIMSELF AND JAMES D. ULERY, OF SAME PLACE.

Letters Patent No. 96,948, dated November 16, 1869.

IMPROVEMENT IN SAWING-MACHINE.

The Schedule referred to in these Letters Patent and making part of the same.

To all whom it may concern:

Be it known that I, WILLIAM OLLER, of Scenery Hill, in the county of Washington, and State of Pennsylvania, have invented a new and improved Scroll-Sawing Machine; and I do hereby declare that the following is a full, clear, and exact description of the construction and operation of the same, reference being had to the accompanying drawings, making a part of this specification, in which—

Figure 1 is a side elevation, and

Figure 2 is a transverse vertical section.

This invention consists in mounting a saw in a frame consisting of two pairs of metallic levers, one pair at each side of the saw; said levers having their fulcra at the top and bottom of vertical metallic bars, placed one at each side the saw, and said levers being connected with the saw by springs at the top and bottom, and the upper pair of levers being connected with the lower pair at their outer ends, by means of extensible rods, by which the frame may be tightened or loosened, at pleasure, and is made at once strong, flexible, and elastic, so as to admit of all the necessary movements of the saw.

In the drawings—

A is the wooden frame-work in which the machine is mounted, the gearing by which the motive-power is applied, being seen at the lower part of the same.

A rod, *a*, connects the crank-shaft with the saw-frame.

The metallic saw-heads *b b* have each two hooks, *b'*, one at right angles to the other, so that the saw may be placed in either direction, and act either as a scroll or as a cross-cut-saw, at pleasure.

My saw-frame is a peculiarly novel and ingenious arrangement.

It consists of two metallic bars *c c*, oblong in cross-section, and pointed at top and bottom, as shown in fig. 1; said bars being firmly fixed in the upper main cross-beam *B*, and projecting both above and below the same.

The pointed ends of the bars *c* form the fulcra for four metallic levers *d d' d' d*, which have transverse grooves for the reception of said pointed ends; said levers being connected, at their inner ends, by means of spring-plates *e e' e'*, with the upper and lower saw-heads, and the upper and lower pairs of levers being jointed at their outer ends, by means of extensible connecting-rods, each of said rods being made in two parts, connected by a screw-bolt, *h h*, so that the connecting-rods may be shortened or lengthened at pleasure, for the purpose of tightening or loosening the frame.

The frame thus constructed possesses sufficient flexibility and elasticity to assume all the varying changes of shape necessary in the rise and fall of the saw, and without opposing any hindrance to the motion of the saw, is strong enough to carry the latter through all the movements required of it.

The fulcra of the levers *d d'* being pointed, the latter move with the least possible friction.

The mechanism may be driven by any sort of power, from a treadle to a steam-engine.

I am aware that the several parts herein described, separately considered, are not new, and I therefore wish it to be understood that I do not claim them; but having thus described my invention,

What I do claim as new, and desire to secure by Letters Patent, is—

The bars *c*, levers *d d'*, spring-plates *e e'*, and extensible connecting-rods *h*, combined and arranged, in connection with the cross-beam *B*, substantially as described.

To the above specification of my improvement, I have set my hand, this 21st day of April, 1869.

WILLIAM OLLER.
